UNITED STATES PATENT OFFICE.

CHARLES S. WELLS, OF HERRICKVILLE, PENNSYLVANIA.

WHIFFLETREE.

SPECIFICATION forming part of Letters Patent No. 504,822, dated September 12, 1893.

Application filed May 26, 1893. Serial No. 475,602. (No model.)

To all whom it may concern:

Be it known that I, CHARLES S. WELLS, a citizen of the United States, residing at Herrickville, in the county of Bradford and State 5 of Pennsylvania, have invented a new and useful Whiffletree, of which the following is a specification.

This invention relates to whiffletrees, and has for its object to improve devices of this 10 class by making the same of three pieces of steel put together in such shape as to brace against each other so that one piece cannot become broken without breaking all of the pieces, and the device is so arranged that it 15 is interchangeable from one device to another and is provided with a yielding center-bolt that acts as a swivel.

With these and other objects in view, the invention consists of the construction and arrangement of the parts thereof as will be hereinafter more fully described and claimed.

In the drawings: Figure 1 is a perspective view of the improved whiffletree. Fig. 2 is a 20 section on the line $x-x$, Fig. 1. Fig. 3 is a section on the line $y-y$, Fig. 1. Fig. 4 is a bottom plan view of the device.

Similar numerals of reference indicate corresponding parts in the several figures of the drawings.

Referring to the drawings, the numeral 1 designates a centrally-located steel bar, that is projected at its center toward the front and has its ends deflected toward the rear. In rear of the said bar 1 is a pair of steel 25 bars 2, that are spaced apart from each other vertically and arranged parallel, the space between the said bars being greater at the center and from thence said bars converge toward each other and embrace the outer 30 ends of the bar 1, the latter standing centrally of the two bars 2 and shaping there- with a triangle. The bars 2 are projected rearward a greater distance at their centers and extend forwardly at their ends, and the 35 outer ends of the said bars 1 and 2 are secured together by malleable metal end-sock- 40 ets 3, each of which has a pair of holes 4 therein to adjustably receive a clevis or link 45 5, to thereby provide for adjusting of the 50 said clevis or link to give one horse an ad-

vantage over another, if necessary. Over the central part of the two rear bars and the front bar is mounted and secured a pair of V-shaped tie-braces 6, that are bent around the bar 1 and terminate on opposite sides of 55 the bars 2. The said braces 6 are spaced apart, and between the same and the said bars 1 and 2 is mounted a coiled spring 7, having a washer 8 against the rear end thereof that abuts against a stop-plate 9, bent over 60 and held on the bars 2, the said stop-plate having an opening therein through which is passed a bolt 10, and extended through the washer 8 and the central part of the spring 7. The outer end of the said bolt 10 is formed 65 or provided with a square head 11, that rests against a washer 12, placed against the outer end of the spring and normally forced against the inner edge of the front bar 1; and it will thus be seen that the said spring 7 is confined 70 between the bars 1 and 2, and has at its rear end bearing upon the stop-plate 9, that is disposed vertically. The rear end of the bolt 10 is bifurcated, as at 13, and provided with a removable bolt 14, which, as shown, has a 75 hook 15 movably connected thereto. The bifurcated end of the bolt, together with the mounting of the bolt in the spring in the manner set forth, provides a yielding or spring swivel, and it will be understood that 80 the hook can be removed from the bifurcated end of the bolt and the latter connected directly to a plow, the tongue of a wagon, or elsewhere, as may be found desirable. Covering the bottom of the central portion of the 85 bars 1 and 2 is a wear-plate 16, of iron or other suitable metal, to shield the spring and keep the same from wearing out when drawn upon the ground, or to prevent breakage of the spring when dropping the whiffletree 90 upon the ground.

One important advantage of the device is the yielding nature of the bolt 10, as the load is constantly balanced on a spring, which would take all the jar from the shoulders of 95 the horses with evident advantages.

The device is simple and effective in its nature and exceptionally strong and durable; and it is obviously apparent that changes in the form, proportion, and the minor details 100

of construction may be resorted to without departing from the principle or sacrificing any of the advantages of this invention.

Having described the invention, what is claimed as new is—

1. In a whiffletree, the combination of three triangularly-arranged bars, two being located at the back and one in front in the central plane of the said back bars, metallic sockets receiving and connecting the outer ends of said bars and provided with holes to adjustably receive a clevis or link, a bolt loosely mounted on the bars and extending rearwardly from them, a hook pivoted to the rear end of the bolt, and a cushioning spring interposed between the front end of the bolt and the back of the whiffletree, substantially as described.
2. In a whiffletree, the combination of three triangularly-arranged bars, two being located at the back and one in front in the central plane of the said back bars, outer end sockets connecting said bars having links or clevises attached thereto, a pair of V-shaped tie-braces passing over the front single bar and terminating at the rear back bars, said tie-braces being spaced apart from each other, and a central attaching bolt, substantially as described.
3. In a whiffletree, the combination of tri-

angularly-arranged bars, two being located at the back and one in front in the central plane of said bars, a pair of V-shaped tie-braces passing over the central portions of said bars, a spring-encircled bolt mounted between said bars and braces and having a rear projecting bifurcated end, a vertically-disposed stop-plate against which the rear part of said spring rests, said bolt having a front angular head bearing against a washer placed against the front of said spring, and a bolt removably mounted in said bifurcated end of the aforesaid bolt, substantially as described.

4. In a whiffletree, the combination of triangularly-arranged bars having a centrally-positioned bolt surrounded by a coiled spring, a pair of tie-braces connecting said bars at the center and spaced apart, and a wear-plate secured over the bottom of the said bars and attached to the said braces to shield the spring, substantially as described.

In testimony that I claim the foregoing as my own I have hereto affixed my signature in the presence of two witnesses.

CHARLES S. WELLS.
